ADHESIVE STRIP SERVER

Trevor R. Gautier and Robert W. Hoitt, Nashua, N. H., assignors to Nashua Gummed and Coated Paper Company, Nashua, N. H., a corporation of Massachusetts

Original application January 9, 1943, Serial No. 471,890. Divided and this application March 15, 1944, Serial No. 526,582

14 Claims. (Cl. 91—14.5)

1

The present invention relates to devices and apparatus for measuring, adhesively conditioning and delivering selected lengths of adhesive paper and like tape, from supplies of indefinite length, the successive strip lengths being delivered in condition for adhesive affixing for package sealing and other purposes. More particularly the invention aims to provide an extremely compact machine of the class described, of rugged construction and efficient operation, and wherein the actuating parts are protected and concealed in an enclosure having a minimum of projecting parts and presenting an attractive "streamlined" appearance, rendering the machine appropriate to store counters, office desks and like locations where space saving and pleasing appearance, as well as sturdiness and reliable operation, are important considerations.

This application is a division of our copending application Serial No. 471,890, filed January 9, 1943 and which has matured into Patent No. 2,382,787, issued August 14, 1945.

In the drawings illustrating by way of example one embodiment of the invention:

Fig. 1 is a side elevation of the machine or device as a whole, on a smaller scale than in following views;

Fig. 2 is a longitudinal vertical section taken just inside the right side frame;

Fig. 3 is a plan, with the cover removed and the right side plate sectioned;

Fig. 4 is a horizontal section as on the line 4—4 of Fig. 2;

Fig. 5, on a larger scale, is a vertical longitudinal section substantially centrally through the machine, with the rear end broken away;

Figs. 6 and 7, on Sheet 1, are vertical cross-sections, Fig. 6 being taken near the front or delivery end of the machine as on the line 6—6 of Fig. 2 and looking forwardly, while Fig. 7 is taken near the rear of the machine as on the line 7—7 of Fig. 2 and looking rearwardly;

Fig. 8 is an exploded view of elements of the measuring and feeding mechanism;

Fig. 9 shows in side elevation a portion of the inner face of the operating lever;

Figs. 10 to 12 are detail views of a tape feed guide and moistener assembly unit, separately, in plan and in rear and side elevation respectively;

Figs. 13 to 16 are a related series of elevational views of frame or cover elements separately, wherein

Fig. 13 shows the inside face of the side cover plate;

2

Figs. 14 and 15 represent the inner faces of the right and left frames, respectively, and

Fig. 16 shows the inner face of the front door or cover;

Fig. 17 is a front end elevation of the machine as a whole, on the scale of Fig. 1; and

Fig. 18 is a companion view to Fig. 17, showing the rear end.

Referring to the drawings in more detail, the machine comprises a combined frame and housing seen in full assembly in Fig. 1 and as to its various component elements in the other views. The housing as illustrated comprises two main longitudinal or side frames 1 and 2, a removable side cover plate 3, herein at the right, a top cover 4 and a front closure and delivery table 5, both the latter arranged to be swung open for access to adjacent parts. These several elements of the housing have each an integral one-piece construction, being formed preferably by die casting of a zinc or other metal composition or alloy or by molding of a plastic composition. In this manner the side frames 1 and 2 and the side plate 3 are made to present at their inner faces all the reinforcing ribs, fins and such formations and the various lugs, bosses, projections and the like as appropriate for the mounting and positioning of the operating parts to be described, and for readily and demountably securing together the housing elements, thus providing a smooth surfaced and pleasing exterior for the resulting portable machine unit.

Noting particularly Figs. 1, 17 and 18, the housing has none of the usual externally visible securing means such as nuts, bolts, screws, clips and the like connections. It is also noted that the side plate 3 is so shaped and correlated with the adjacent frame member 2 as to match externally with the opposite one-piece side frame 1, affording a well-balanced structure of symmetrical and attractive contour as viewed from any angle.

These side frames 1 and 2 are respectively formed with inwardly extended rear ends 1a and 2a adapted to abut laterally in opposed relation to provide an enclosing lower rear wall for the housing. These frames are separable joined by a minimum of interconnections, to be referred to in connection with the various other functions which they serve. Along their lower edges the side frames 1 and 2 are formed with base flanges 1b and 2b provided with cushioning pads 6, 6, etc. of rubber or other resilient composition, desirably recessed at their underface for increased holding effect, and securely set into conforming

inverted sockets 7, 7, etc. in the side frame bases.

At the rear portion of the machine, the space between the side frames 1 and 2 and within the overlying portion of the conforming inverted trough-like top cover 4 provides a chamber for a supply of the adhesive tape or strip in roll form, as indicated at T, Fig. 2, positioned in this chamber in readiness to be drawn upon. Such supply roll is supported on a combined floor and under-guide 8 comprising a single piece of metal or other strip material continuous from the rear of the tape supply chamber to and beyond the rotary tape-engaging elements of the feed means to be described. The rear end of this tape support and guide 8 serves as one interconnection for the side frames. For this purpose it is lapped horizontally against projections 9, 10 on the frame rear walls 1a, 2a and there secured as by nuts and bolts 9a, 10a, Figs. 2 and 4. This guide flooring 8 has a width adapting it to space and brace the side frames. It is positioned vertically and also lengthwise by a series of locating nubs 11, 12 projecting from the respective side frames and distributed along the adjacent edges of this guide flooring 8, some below and others above the latter; Figs. 3, 4, 5, 14 and 15.

The top cover 4 extends nearly the full length of the machine. Its front end terminates at and in part defines the delivery station for the moistened measured lengths of tape to be dispensed. This cover is readily removably hinged at the rear of the side frames. The latter have opposed sockets 1c, 2c, Figs. 3, 14 and 15, for horizontal plug-like pivot pins 4a. Noting Figs. 2, 3 and 7, these pins are each of a length to extend through aligned bearing apertures in vertical flanges 4b projecting forwardly from a tongue 4c depending from the base of the rear wall 4d of the cover 4. These pivot pins 4a are of reduced diameter at their inner ends to provide abutment shoulders for the opposite ends of a retaining spring 4e. By merely unseating this spring, the cover pivot pins may be withdrawn inwardly, permitting the cover to be removed bodily and as easily restored. Reinforcing ribs 4f at the inner faces of the cover, Figs. 2 and 5, are projected below its side edges as feet 4g to aid in firmly positioning the cover laterally on the respective side frames. The lower edge of the cover tongue 4c is rounded and the adjacent horizontal upper edges of the frame rear walls 1a, 2a are correspondingly arcuately beveled, as at 1d, 2d, Figs. 14, 15, to provide an overlapping joint in the closed position of the cover 4. The latter is stopped and held in its substantially vertical full-open position by engagement of the outer face of its tongue 4c down upon the top of the frame rear walls 1a, 2a.

Tape rolls of different widths within the capacity of the machine are laterally centered in the supply chamber by means of adjustable side guides or plates 13, 14, Figs. 2 to 4, 5 and 7. These plates are slidably and pivotally mounted at their upper forward portions on a crossbar 15 having its opposite ends removably supported in aligned bosses 16, 17 on the respective frames 1 and 2; see also Figs. 14 and 15. The floor member 8 further serves in positioning these lateral guides 13, 14. For that purpose it has a series of transversely spaced slots 18 at its forward portion, and a corresponding longitudinally aligned rear series of spaced slots 19. The guide plates 13, 14 have down projections at their forward ends, and other depending members at their lower rear portions, adapted for positioning reception in any selected aligned pair of the for-

ward and rear slots respectively; see for example 14a and 14b as to plate 14, Figs. 2 and 5, the other plate being similar. By lifting the guide plates about their supporting bar their slot-entering portions are disengaged, permitting the plates to be shifted laterally as appropriate for the particular width of tape, such as $\frac{3}{4}$, 1, $1\frac{1}{4}$, $1\frac{1}{2}$ inch, etc.

The floor and under-guide 8 also has formed in its forward portion an elongated central slot 8a, Fig. 3, giving access to the underface of the tape by the driven feeding and measuring wheel or roll 20, Figs. 2 to 5 and 8. This lower feed wheel 20 acts in cooperation with an overlying and herein relatively smaller feed wheel or roll 21, to engage, measure out and advance the tape between them and past the severing and the moistening means, for delivery in moistened condition at the front end of the machine.

The upper feed and measuring roll 21 is mounted on a combined roll carrier and tape guide, herein formed as a unitary casting; Figs. 2 and 3. It comprises a pair of laterally spaced rearwardly projecting ears 22, 22 holding a pin 23 on which the upper roll 21 is freely rotatable. This carrier and tape guide unit further includes an upright portion 24 and a bottom foot or plate 25 projecting laterally beyond the ears 22 and having a smooth flat underface to serve as a top guide for the tape immediately forward of the feed rolls. The upper roll 21 is of a size and so located on the carrier as to project below the guide foot 25. Thus with the roll in its operative position against the lower feed roll 20, or in contact with the tape between them, the guide foot 25 is properly spaced vertically to define with the forward portion of the flooring 8 a chute or guide for the tape advanced forwardly beyond the feed rolls.

The upper roll carrier further comprises a transverse bearing 26 above the ears 22 and an upright portion 24, for reception loosely on a cross shaft 27, Fig. 5, said cross shaft serving as a horizontal pivotal support for the upper roll carrier 45 as a whole and also as a cross connection between the side frames 1 and 2. For this purpose the frames have at transversely opposite upper portions upright brackets 1x, 2x, Figs. 14, 15, apertured for screws 27a, 27b, Fig. 3, tapped into the 50 respective ends of the cross shaft 27.

This cross shaft also supports spring means for pressing the upper feed roll 21 against the tape and keeping it in feeding and measuring relation to the lower roll or wheel 20. Such spring 55 means herein comprises a pair of duplicate coil springs 28, 28 set on the shaft 27 at opposite sides of the roll carrier, between the latter and the side frame brackets 1x, 2x, see particularly Figs. 2, 3 and 5. These springs have rear legs 28a, 28a hooked over the respective ends of the roll pin 23, and forward legs 28b, 28b tensioned across the upper edge of a cross member 115 the bottom edge of which provides the fixed cutter element of the tape severing means, to be described. For lifting the upper roll 21, and with it the top guide plate 25, to expose the tape path for 60 inspection and cleaning purposes, the roll carrier has an upwardly and rearwardly projecting lifting lever 29 formed integrally with the roll carrier unit and presented for convenient engagement by the operator's fingers, on opening the housing cover 4.

Novel means, of extremely compact construction and arrangement, is provided for actuating 65 the feeding and measuring mechanism, in asso-

ciation with the moistening and severing means. Referring to Figs. 2, 4, 5 and 8, the lower feed roll or wheel 20 is mounted to rotate, in the forward or feeding direction, counter-clockwise in Fig. 2, on a stationary main shaft 30. At the left of the machine said shaft is held in a recessed boss 31 on the side frame 1, see particularly Fig. 14, while its opposite end projects freely through a bearing aperture 32 in the frame 2 and laterally out through an opening 33 in the side cover plate 3; see also Figs. 13 and 15. The feed wheel 20 has at its left face, Fig. 4, an elongated hub 20a loosely received on the shaft 30, the hub together with a washer spacing the wheel relative to the frame 1 so as to present it centrally of the tape path.

At its other face the feed wheel 20 carries a pawl 35 pivoted on a stud 36, as best seen in Figs. 2 and 8. A flat spring 37 having one end bent to engage around a button 38 on the wheel 20 presses the pawl toward the wheel axis. A similar button 39 depresses the spring at an intermediate point, to tension it. If desired, a shifting pawl such as that of Gautier Patent 2,290,041 may here be employed.

The pawl 35 coacts with a ratchet disk 40 so that the wheel 20 receives rotation in the forward, feeding direction (counter-clockwise in Figs. 2 and 8) but is left at rest during reverse return rotation, clockwise, of the ratchet disk and associated gearing. This ratchet disk 40 is mounted to turn on the cross shaft 30, which also carries the further train of operating parts to be referred to, all rotatable on it.

At the right side of the ratchet disk 40 and separably connected to turn with it is a coupler 41 having connector lugs 42 at its inner end for reception in corresponding recesses 43 in the ratchet disk. At its other end the coupler 41 has similar connector lugs 44 fitting in recesses 45 in the hub of a pinion 46. This pinion, the coupler 41 and the ratchet disk 40 accordingly rotate as a unit. The coupler 41 and the pinion 46 have a joint extent along the shaft 30 so as to fit snugly between the feed wheel 20 and the right side frame 2, all the described parts on the shaft 30 consequently being correctly located and held laterally by and between the two side frames.

The feeding and measuring means, as well as the cut-off mechanism, to be described, are operated by the hand lever or operating lever 50 disposed conveniently to the operator's hand and having a finger-engaging piece 51 at its fore end resembling a button or push-key; Figs. 3 and 4. This hand lever, herein at the right side of the machine, is the only exposed moving part, as evident in Figs. 1, 17 and 18. For assembly purposes it is associated with the side cover plate 3, so as to remain with the latter during removal and replacement of the plate.

Accordingly the hand lever 50 has at its lower end a lateral hub 52 adapted to extend through a corresponding aperture 53 of a boss 53a on the side plate 3, see also Fig. 13, said plate aperture having horizontal radial recesses or slots 53b. The lever hub 52 has at its inner end a pair of inwardly and also radially projecting lugs 54, 54, best seen in Figs. 8 and 9. At the outer face of the side plate, between it and the lower end of the lever, is a thrust washer 55 centrally apertured at 56 for reception on the lever hub 53 and having radial recesses 57, 57 for passage of the lever hub lugs 54 in assembling the washer. After this washer 55 is passed onto the lever hub the washer is given a quarter turn, bringing its

radial recesses 57 out of line with the lever hub lugs 54, and into line with a pair of shallow lugs 54a at the inner face of the lever; see Fig. 9. These enter the washer recesses 57 and hold it against turning relative to the lever. The lever hub is then inserted through the apertured boss 53a of the cover plate 3, the hub being positioned with its lugs 54 horizontal, in line with the radial recesses 53b of the cover plate. A second washer and lock ring 58, with similar central aperture 58a and radial recesses 58b is then passed onto the lever hub, at the inner face of the cover plate and given a quarter turn to carry its recesses out of line with the lever hub lugs 54. This brings a non-recessed portion of the lock washer 58 behind the lever hub lugs, between them and the cover plate. Thus the lever is demountably locked in assembled position on the plate, yet left free to swing in the vertical plane relative to it.

In some instances, particularly where, as here shown, the radial lugs 54 of the hand lever 50 are out of line with the cover-plate slots 53b in all operative positions of the hand lever when the cover plate is in place, either or both of the outer and inner washers 55 and 58 may be dispensed with. In such case the hub of the hand lever may have a slot-covering flange corresponding to the outer washer 55 formed integrally with it, while its lugs 54 may be appropriately extended axially by substantially the thickness of the inner washer 58.

In addition to the feed elements described, the shaft 30 also provides bearing support for the hand lever 50 and for the operating element or crank 60 which transmits motion from the hand lever to the other actuating parts. This crank 60, of a general bell-crank form, has fixed on it a laterally extended bearing portion or sleeve 61 rotatably received on the projecting end of the shaft 30. The hand lever hub 52 is centrally recessed to receive this crank bearing sleeve 61 and the enclosed end of the shaft 30, so that the sleeve and shaft afford the bearing support for the hand lever, rather than the side plate 3. The side plate 3 itself is demountably secured to the side frame 2 by a number of screws 3a extending out through the latter into bosses 3b at the inner face of the cover plate 3; see Figs. 4, 7 and particularly Fig. 13.

The crank or main actuating element 60 is directly associated with the hand lever 50 and is seen separately in Fig. 8. It comprises a rear arm 62 having a stop foot 63 at its outer end, an intermediate depending arm 64, and a forwardly extended length-control arm 65.

The body of the crank 60 adjacent its sleeve bearing has a pair of radial recesses 66, 66 which receive the lugs 54, 54 on the hand lever 50. Thus in the assembled position of the parts the hand lever is directly connected to the crank in fixed angular relation to it.

The central arm 64 of the crank 60 has at its lower end a lateral boss 67 which extends in through and is longitudinally movable in an opening 68 in the adjacent side frame 2; see Fig. 15. The crank boss 67 is apertured as at 67a, see Fig. 8, to support a stud 69 having at its inner end a bearing 69a for rotatably mounting a traveler gear 70, desirably of a light weight but resistant material such as fiberoid or other composition.

As the crank 60 is rocked about the shaft 30 as an axis, by vertical movement of the hand lever 50, the traveler gear 70, being carried on

the crank by the stud 69, is swung bodily lengthwise of the machine and along an arc about the crank axis. Vertically below the gear 70 is an arcuate toothed rack 71 integrally cast or otherwise fixed at the inner face of the frame 2 as by rivets 72 received in bosses 73 thereon; see Figs. 2, 5, and 15. This toothed rack 71 is shaped and positioned to be concentric with the crank axis, namely, the shaft 30, so as to have meshing engagement with the gear 70 throughout its bodily reciprocating movement lengthwise of the machine. This gear 70 also is proportioned to mesh constantly with the previously mentioned pinion 46 on shaft 30. Accordingly, as the gear 70 is bodily traveled lengthwise of the stationary rack 71 by movement of the hand lever 50, it is also forced to rotate on its own axis, and in so doing also to rotate the pinion 46 and with it the feed wheel 20.

This drive gearing has a high ratio, such that a small angular movement of the hand lever 50 affords a substantially increased rotation of the feed wheel 20. In the illustrated example, the hand lever has a maximum stroke of only about 45°. But in making such relatively short stroke it may impart several full rotations to the driven feed wheel 20. Accordingly the length of tape obtainable by a single stroke of the hand lever has a correspondingly wide range, as calculated for the given size of machine and the particular field of use. Merely by way of example, with a feed wheel 20 of but about a two-inch diameter the described construction and arrangement of hand lever gearing connections gives accurately measured tape lengths from about 2 inches up to 6 and 8 inches or more.

As more fully disclosed in our said parent application the machine desirably is equipped with means for setting it to dispense various different predetermined tape lengths. In its normal rest or up position the operating lever 50 stands substantially as in Figs. 1, 5, 17 and 18, to which it is automatically returned on release following a feed stroke, such position being determined as by a return stop 75, Fig. 4, held by fingers 76 on the side frame 2, Figs. 4 and 13, and cooperating lugs 77 in the cover plate 3, Fig. 13. This stop block is disposed to abut the foot 63 on the rear arm 62 of the crank 60, previously described, see particularly Figs. 3, 4 and 8. Similarly as in said earlier application, the feed-length selecting means may comprise a control arm 65, Figs. 3, 4 and 8, having a series of shoulders or stops 80 to 83 selectively engageable with a selector device 84, Fig. 6, pivotally supported by a lateral boss at its upper end received in a bearing collar 86 on the side frame 2. A lateral stop finger 87 at the lower end of this selector 84 is adapted to be set, by pivotal movement of the selector, to bring it into opposition to any desired one of the stop shoulders 80 to 83. The selector may be held in a desired position as by means of a spring detent 88, Fig. 6, engageable in the appropriate notch of a segment 89 near the base of the side frame 2. The selector 84 carries a pin 94 which extends out through a slot 95a in the side plate 3, Fig. 1, and terminating in the setting button or the like 95. The side plate may be marked with a scale of feed lengths, such for example as 3, 4, 6, 8, adjacent the setting button.

The hand lever is automatically returned to its rest position of Figs. 1, 5, 17 and 18 by suitable spring means, herein comprising a first or main spring 100 of the retraction type, the upper end of which is seen in Fig. 3. Desirably also

5 a second or compensator spring device of the expansion type may be provided, as fully disclosed and claimed in our said parent application and not necessary here to consider in further detail, the action of such means in combination with the main spring 100 being such as to afford the desired effort for the lever at different portions of its stroke and irrespective of the total stroke length.

15 Turning now to the severing of the measured lengths of moistened tape, the mechanism for this purpose is operatively associated with the described feeding, guiding and measuring means, and preferably and as herein shown is actuated automatically through the medium of the hand lever 50.

20 The cutter element comprises a fixed blade 115 transversely positioned on the frames 1 and 2 with its lower edge just above the tape path, in shearing relation to the movable blade 116. At its left end, Fig. 3, the fixed member 115 has a reduced portion 115a received in a seat 115b, Fig. 14, on the frame 1, while its right end projects laterally through an opening 117 in frame 2, Fig. 15, and is supported by bracket 118 on the latter carrying a stud 119 extending through both blades and providing the pivot for the movable blade 116. The movable blade 116 normally occupies a position clear of and herein below the path of the tape, and in cutting the tape it is raised so as to make a rapid up cutting stroke with immediate return. This is effected by a trip mechanism and operating connections associated with the hand lever 50 through the medium of the crank 60 already described.

25 As more fully described in our parent application, and noting particularly Figs. 2 and 5, also Fig. 8, the pivot stud 69 for the traveller gear 70, which stud is mounted in the aperture 67a of the intermediate depending arm 64 of the crank 60, Fig. 8, is laterally extended and has fixed on it a depending finger 120 carrying at its lower end a cam roll 122.

30 Noting Fig. 5, this cam roll finger 120 swings rearwardly during a feed stroke of the hand lever 50, and during its subsequent return movement said finger 120 cooperates with the cutter actuating means comprising a trip lever 123 having at its rear end a bearing collar 124 rockably received on a stud 125 in a boss 126 on the side frame 2; see Fig. 15. The front end of this trip lever 123 is connected to the movable blade 116 by a link 127, Figs. 2 and 5, pivoted to said parts at its opposite ends in a manner affording the link a pivoting movement both laterally and longitudinally of the machine; Figs. 2 and 5.

35 Actuation of the trip lever 123, on forward return movement of the finger 120 in conjunction with the hand lever return, is effected by a dog or trip member 130, see particularly Fig. 5, pivoted at 131 upon the trip lever 123. The front and rear arms 132, 133 of this dog overlie stops 134, 135 on said lever which limit vertical rocking movement of the dog. This dog, illustrated as of a general triangular shape, has front and rear oppositely inclined cam faces 136, 137, the latter presenting an abrupt shoulder 137a.

40 In the normal or rest position of the parts, hand lever 50 being elevated as in Figs. 1 and 5, the cam roll 122 stands in front of the forward cam surface 136 of the pivoted dog 130. As the hand lever 50 is depressed for a feed stroke, the cam or trip finger 120 through the medium of the crank 60 is swung rearwardly, toward the left in Fig. 5. During this movement the pivoted

dog 130 is lifted idly, to an extent limited by the front stop 134 on the trip lever 123, the cam roll 122 passing under the lowest portion of the dog so as to be brought behind its rear cam surface 137.

As the feed stroke of the hand lever continues, the finger 120 and its cam roll 122 move on back away from the dog 130, the latter tipping back to its initial position as defined by down engagement of its rear arm 133 with the corresponding stop 135 on the trip lever 123. This down movement of the dog takes place by gravity, since the portion of the dog behind its pivot 131 is the heavier. In the illustrated construction it is accelerated and made certain by the knife and trip-lever return spring 140, which has its lower end connected to the front arm 132 of the dog as by a pin 132a thereon and its upper end connected to a portion of the movable blade 116 remote from the pivot of the latter.

The extent of movement of the trip finger 120 rearwardly past the dog depends on the degree of depression of the hand lever 50, in accordance with the selected tape length to be measured out. But regardless of the length of tape delivered within the available range, the construction and arrangement of the parts herein is such as to insure that the trip finger is thus preparatorily carried to the rear of the dog during an early part of the given feed stroke, including the shortest.

On release of the hand lever 50 at completion of a down or feed stroke, its described return means causes the trip finger 120 to return forwardly, toward the left on Fig. 2 (toward the right on Fig. 5). In the course of this return movement, when the tape feed has been completed and the tape accordingly is at rest, the cam roll 122 engages the rear inclined face 137 of the dog 130, strikes the abrupt shoulder 137a of the latter, and thrusts the trip lever 123 sharply and rapidly upward. The trip finger 120 and its cam roll 122 continue their forward return during a remainder of the hand lever return movement, the cam roll passing forwardly beneath the lowest portion of the dog so as to bring the latter again to its initial or rest position of Fig. 5 in front of the dog 130 and immediately below its forward inclined face 136.

Through the described pivotal link connection 127 between the trip lever 123 and the movable blade 116 it will be seen that the quick positive upthrow of the trip lever 123 affords an extremely rapid shearing action for the blade, with substantially instantaneous release and return thereof to its normal position clear of and herein below the tape path, in immediate readiness for severing a succeeding length of tape.

As in our said parent application, a slight lost motion may be provided between the trip finger 120 and the crank 60, as also between the hand lever 50 and the driven feed wheel 20, as by appropriate clearance between the hand lever lugs 54 and the recesses 66 on the crank in which they are received; Fig. 8. Of if preferred, a shifting pawl, such as that of Gautier Patent No. 2,290,041 may be employed, either alternatively or in addition to such lost motion provisions, thereby insuring against interference with the cutting action by occasional rebound of the hand lever.

The movable blade 116 and the trip lever 123 are together returned to and normally held in their down position, as in Fig. 5, by means of the coil spring 140 which interconnects them. This spring 140 has a vertical bodily movement with

the blade and the trip lever 123, during which it also is extended and further tensioned. In the down or rest positions of these parts, the spring normally stands under some tension, holding the blade and the trip lever as closely together as their interconnecting link 127 permits. Since such condition of relative approach of the blade and the trip lever can only be had with the blade open or down, the spring normally pulls and holds the blade down, and through the link 127 likewise depresses the trip lever 123.

The lower end of the link 127 is more remote from the lever pivot 125 than the upper end of the link is from the blade pivot 119. Hence for a given angular up movement of the lever 123 the link accords a greater angular movement to the blade 116. At the same time the free end of the blade, including the attaching point 141 (Figs. 2 and 5) of the upper end of the spring 140, which is more remote from the blade pivot than the upper end of the link 127 is, receives a greater lineal up movement than does the lower end of the spring by its connection to the lever 123 through the dog 130.

Consequently the spring is extended and additionally tensioned during up movement of the blade and its trip lever 123. But as soon as the cam roll 122 has cleared the dog 130, forwardly, the spring 140 is free to contract. To do so it must bring the blade and trip lever closer to each other, to the extent which the link 127 allows. The effect is to pull down the blade, and, through the link 127, to thrust down the trip lever, into the rest position of Fig. 5. Down movement of the trip lever 123 as well as that of the blade, is halted in this position by a fixed stop, herein comprising a pad or cushion 142 on a bracket 143 projecting from the adjacent face of the frame 2; Fig. 5.

It will be seen also that the spring 140 has a rearward and downward inclination, its lower end being anchored somewhat to the rear of the pivoted blade 116. Thus it has a component force effective to bias the movable blade toward the fixed blade 115, affording them an efficient cooperative shearing action.

At an earlier point we have described means including the resilient back-stop or buffer 75 for halting the return motion of the hand lever and associated reciprocating parts of the feed action. In some instances, particularly where a rapid return stroke is desired, yet without attendant objectionable rebound or overfeed, such means may be supplemented by, or have substituted for it, means affording a braking or positive stopping action on and through a rotary member of the feed mechanism.

Herein for the purpose such arrangement is shown in connection with the intermediate or traveller gear 70. As seen in Fig. 5 said gear 70 has at its inner face, its face adjacent the cam-roll arm or finger 120, a laterally projecting stop member such as the pin or screw 70a. In the normal or rest position of the parts this stop 70a stands against the forward edge of said arm or finger 120, substantially as in Fig. 5. As the gear 70 travels bodily rearward along the rack 71 in the course of a feed stroke, the rotation of the gear carries the stop 70a away from said finger 120, counterclockwise as viewed in Fig. 5. On release and return of the hand lever 50 and with it the gear 70, the stop 70a returns rotatively to its initial or rest position of Fig. 5 bringing up positively against the forward edge of the finger 120. Further rotation of the gear 70

being thus positively blocked, the gear cannot move further forward along the rack and accordingly further rearward return motion of the hand lever 50 is positively stopped. The energy of the halted parts is taken up in part by the lost-motion mounting of the finger 120 previously referred to and by the interengaged gear and rack, substantially eliminating any tendency for the gear to turn reversely, in the feed direction.

Where such positive stop means as afforded by the stop 70a is employed in combination with a buffer element such as the resilient back-stop 75, these two elements are so relatively arranged that the buffer-engaging member, herein the foot 63 on the arm 62 of the lever-operated crank 60, will engage the buffer 75 substantially simultaneously with or a brief instant after the striking of the stop 70a against the finger 120. Thus the momentum of the parts in the return direction may largely be absorbed by the buffer but with little or no actual compression of the latter. The result is an extremely positive stopping action, substantially without rebound or tendency of overfeeding of the tape at the end of a lever return stroke. In some instances the buffer means such as 75 may be dispensed with. In such constructions, or under the provision of the joint stopping elements as herein illustrated, the stop pin or screw 70a may carry a fibre or other collar for the direct contact with the engaged element such as the roll arm or finger 120.

As previously indicated, the tape from the supply roll T (Fig. 2) is advanced along the under-guide 8, by and between the feeding and measuring rolls 20, 21, the tape passing below the guide foot 25 of the upper roll carrier and forwardly past the severing means and below the fixed blade 115. Beyond this cut-off point the leading portion of the tape is advanced to and past additional guides and correlated means for moistening its gummed (under) face.

Such means comprises a tank or reservoir 150, best seen in Figs. 2, 4, 5 and 6. Desirably it is formed of a plastic transparent or semi-transparent composition permitting the level of the contained moistening liquid to be observed. In this tank is removably set a capillary moistening element, such as the inverted brush 151 resting on its butt 151a. The bottom wall of the tank is projected up, centrally, in an inverted V-formation 152 transverse of the tank. The oppositely inclined walls of this raised formation serve to direct the butt of the brush 151 into correct position in the tank, substantially as in Fig. 5, when the brush is merely dropped into it. The side walls of the tank have central vertical ribs 153 at their inner faces, each with a slot 154 at its upper end to support a removable partition 155, of similar material as the tank or otherwise. The brush 151 is adapted to incline forwardly against this partition, with the free ends of its hair or bristles projecting above the tank. By reason of the removable partition or upper support for the brush all the interior of the tank is readily accessible for cleaning. As thus constructed the tank is reversible end to end, so that the brush may be located in either half section of tank and the latter inserted into the machine, with the then brush-carrying section to the rear. This automatically positions the upper end of the brush in correct moistening relation to the under face of the tape.

Referring to Figs. 2, 5 and 6, the tank assembly as a whole is removably positioned between the forward portions of the side frames 1 and 2, upon

a pair of opposed horizontal ribs 156, 157 on the latter. Inward movement of the tank is limited by one or more lateral projections as at 158, Fig. 2, and it is held against forward displacement by lugs 159, 160 on the respective side frames and having vertical rear faces to abut the lower front wall of the tank. These lugs may also serve as positioning stops for the front closure element 5, together with the outer ends of upper and lower horizontal ribs 161, 162 and 163, 164, Figs. 6, 14 and 15, on the respective side frames. These latter ribs also guide and locate the tank laterally; Fig. 6.

In the closed position of the front closure 5, the tank 150 is held down by a hook-like projection 165 at the inner face of said closure 5, adapted to overlie the top edge of the tank front wall, as best seen in Fig. 5; see also Fig. 16. The tank unit may readily be lifted out from the machine on swinging the front closure 5 to its open position shown in Fig. 5. This front member also affords a convenient location for the name plate 166 held on a rectangular frame 167, Figs. 5 and 16, at the inner face of the closure. Such plate 166 itself serves as a further front positioning means for the tank 150.

As mentioned earlier, this front closure 5 also provides a delivery table or guide for the moistened lengths of tape dispensed by the machine. For this purpose its main wall is turned in at its upper end and is projected rearwardly and somewhat downwardly to form a delivery guide 170. Thus in the normal closed position of this front member 5, as shown dotted in Fig. 5, the rear edge of its tape guide portion 170 stands directly in front of or contacts and assists to support the projecting end of the brush moistener 151. At the sides of the tape path this guide formation 170 of the front closure 5 further includes integral upstanding projections 171, 172 for confining the tape laterally; see also Figs. 3 and 17. The top edges of these lateral guides 171, 172 are disposed along a similar line of upward and rearward curvature as the adjacent portions of the side frames 1 and 2 and of the side cover plate 3, affording a complete and conforming closure for the front of the machine as a whole, the top cover 4 fitting snugly down onto the top side portions of front element 5.

As best seen in Fig. 3, also Figs. 16 and 17, the guide means 170, 171, 172 on the front closure 5 present an open-top trough-like formation the floor of which terminates forwardly in a downwardly rounding portion as at 173 merging into the main vertical wall of this front element. This formation facilitates the delivery and seizure of the moistened, severed lengths of tape as measured out by the machine.

The combined closure and delivery element 5 is pivotally supported by means of a pair of inwardly extending ears 168 at its lower portion, these being apertured in transverse alignment for bearing reception on pivot lugs 169 at the bottom front corners of the frames 1 and 2; Figs. 14-16. This front door-like element is automatically returned to and normally held in its closing position, herein by means of a coil spring 175 having its forward end hooked in an eye 176 integrally formed at the inner face of the closure. The rear end of this front cover spring 175 is engaged in an aperture in a cross bar 177 extending between and bolted to opposed lugs 178, 179 on the respective side frames 1 and 2. This cross bar 177 also serves as a further trans-

verse brace and interconnection for the front portions of the side frames.

Beyond the severing means the advancing tape is directed into contact with the moistener by a guide and presser unit, seen in Figs. 2, 3, 5 and 6 and separately in Figs. 10 to 12. This comprises a bottom plate or floor member 180 extending substantially across between the side frames and longitudinally from a position closely adjacent the movable blade 116 out into close proximity with the upper end of the brush 151. The rear edge of this bottom guide 180 is downwardly inclined as a lip 181 to receive and direct the leading edge of the tape with certainty onto it. Opposite lateral portions of this lip 181 are extended to form supporting collars 182, 183 for pivotal reception on opposed bearing bosses 184, 185 cast on the side frames 1 and 2 and which provide horizontal pivotal support for the guide and depresser unit as a whole. The rear lip 181 on the plate 180 also has a downwardly projecting finger 186 adapted to bear against the front face of the blade 116 at times when the brush and tank have been removed, and thus to keep the guide-depresser unit from dropping down into the space normally occupied by the tank. Hence when the tank is to be reinserted the operator need give no special attention to lifting this guide-depresser unit.

Along its lateral edges the bottom plate 180 has upturned flanges 187, 188 which project forwardly beyond the front edge of the plate and there provide bearing support for the end pintles 189 of a tape presser or depressing element in the form of a circumferentially grooved roll 199 adapted to rest on the top face of the tape opposite the brush, or directly on the brush in the absence of tape between it and the roll.

The roll pintles 189 also provide pivotal support for the top guide plate 191 which cooperates with the bottom plate 180 to present an enclosing chute for the tape. This top plate 191 has upright and forwardly projecting flanges 192, 193 received between the flanges 187, 188 of the bottom plate, both pairs of flanges being apertured in line with the roll axis so as to receive its bearing pintles 189.

These chute-forming guides 180 and 191 have their forward transverse edges substantially in vertical line, closely behind the brush and the presser roll 190, and in such relation to the latter that the tape is directed along a tangent to the under portion of the roll where it seats on the brush. The top plate 191 extends rearwardly over the under plate 180 and has its rear edge 194 deflected upwardly to form with the down-turned lip 181 of the under plate a directive mouth for the tape immediately in front of the cut-off blades. This mouth or entrance to the guide chute 180, 191 is of considerable vertical extent at its receiving end adjacent the blades, so as to insure entrance of the leading edge of the tape into the guide chute despite any possible variations in the vertical level of the tape as it is advanced across the fixed blade 115.

Correct vertical spacing of the guide plates 180 and 191 is maintained at their forward portions by reason of their pivotal interconnection at the pintles 189 of the presser roll 190. At their rear portions such spacing is determined by down projections or stops 195, 196 at the respective sides of the underface of the top plate 191. These desirably are of a rounded form as seen in Fig. 10 to facilitate the lateral guiding and

centering of the tape, particularly that of maximum width for the given machine.

For manipulating the upper guide plate 191 and also the described presser-guide unit as a whole, said plate has secured at its upper face an upright finger piece 197, which also constitutes a weighting element for this entire unit. By grasping this finger piece or button 197, which desirably is a relatively heavy solid metal element, the operator may easily swing the top guide 191 forwardly on its own pivotal support at the presser roll axis and into a position as shown dotted in Fig. 12. This exposes the whole interior of the guide chute between the severing means and the moistener. If then it is further desired to inspect the brush and tank, without necessarily removing them, the entire unit may be lifted and swung rearwardly about the axis provided by the frame lugs 184, 185 on which the under plate 180 is pivoted by its collars 182, 183. This latter axis is the same as that about which the presser-guide unit as a whole has a yielding vertical movement for accommodation of the presser roll 190 to the position of the upper end of the moistening brush, it being noted in this connection that the entire feed chute assembly 180-197 pivots vertically on said fixed axis, which is located at the rear of the unit as a whole and at a point substantially spaced behind the brush and its cooperant presser roll 190.

Thus the roll is capable of a substantial range of vertical adjustment yet the tape is always insured of positive guiding along substantially a straight line from the severing blades up to and between the contact areas of the roll and brush and thence onto the delivery platform 170 of the front closure 5. In all operative positions of this unit its top and bottom guides 180, 191 including their rear mouth have the same fixed relation to the presser roll 190 so as to direct the tape along the same tangential line to the under brush-contacting area of the roll.

From the disclosure herein it will be evident that the invention includes as an important aspect an improved structure and organization for a moistened tape dispensing machine in its entirety, with improved cooperative interrelation of its integrated mechanisms for measuring out and advancing lengths of the tape, for guiding, moistening and delivering them, and for cutting off the measured moistened lengths. In this connection it is noted by way of example that the front closure element 5 partakes directly in the functions of guiding, feeding, moistening and cut-length delivering; and that the fore chute and pressure-moistener roll assembly, itself importantly functioning in the feeding, guiding and moistening actions, also is novelly correlated with the severing means. The invention further comprises sub-combinationally the numerous features of novelty presented by the mechanisms individually.

Our invention is not limited to the particular embodiment as herein illustrated or described, its scope being set out in the following claims.

We claim:

1. In a tape dispenser, a housing including means to support a tape supply, shear means in the housing together with feed and guide means to advance tape from the supply past the shear means, a moisture applicator spaced forwardly of the shear means, a tank for supplying moistening liquid to the applicator, tape guiding means between the shear means and the applicator, and a door-like front member pivotally associated

with the housing and having at its upper portion a trough-like element extending back over a front section of the tank and substantially to the applicator so as to underlie the moistened tape lengths projected beyond the latter.

2. In a tape dispenser, a housing including spaced side frames providing a tape supply chamber, a moisture applicator at a fore portion of the housing to contact the under face of the tape, a reservoir for moistening liquid removably seated on and between the side frames, means to advance tape from the supply to and across the applicator, and a door-like front closure movably mounted on the housing and presenting a guide for the tape forwardly of the moisture applicator.

3. In a tape dispenser, a housing including spaced side frames providing a tape supply chamber, a moisture applicator at a fore portion of the housing to contact the under face of the tape, a reservoir for moistening liquid removably seated on and between the side frames, means to advance tape from the supply to and across the applicator, a door-like front closure movably mounted on the housing and presenting a guide for the tape forwardly of the moisture applicator, and positioning means on said closure co-operable with the reservoir.

4. In a tape dispenser, a housing including spaced side frames providing a tape supply chamber, a moisture applicator at a fore portion of the housing to contact the under face of the tape, a reservoir for moistening liquid removably seated on and between the side frames, means to advance tape from the supply to and across the applicator, and a door-like front closure movably mounted on the housing, said front closure having positioning means co-operable with the reservoir and having its upper portion constructed and arranged as a guide for the tape issuing from the moisture applicator.

5. In a tape dispensing machine, a housing comprising a longitudinally extensive laterally protuberant side frame, a similar but straight side frame laterally spaced from the first, said frames having at their rear ends inturned portions of reduced height adapted to abut each other vertically to provide a lower rear wall for the housing, a top cover pivoted on the frames adjacent said rear wall, a separable side cover plate at the outer face of the second side frame opposite and conformant in size and shape to the protuberant portion of the first frame, and a door-like front closure interposed between the front portions of said frames and mounted on them for movement between open and closed positions, said front closure having a horizontally extending upper portion providing a delivery platform for tape to be projected from the machine.

6. In a tape dispensing machine, longitudinal frames defining between them a main compartment, a removable side cover plate at the outer face of one of said frames, said frame and side cover plate including lateral wall means and together forming an auxiliary compartment, an operating lever having at one end portion a lateral supporting hub, a through aperture in the cover plate for axial entry and rotative movement of the lever hub therein, tape-feed actuating mechanism carried on the frames including an operating element adapted to turn from and return to a given angular position about an axis transverse of the frames, said operating element having an axial bearing portion the outer end of which is concentrically disposed at the cover aperture, said bearing portion and said lever hub mutually formed

for axial telescoping connection with capacity for demounting separation in the axial direction, a radial lug at an inner portion of the lever hub and a corresponding lug-seating formation on the operating element to interlock them for angular movement in unison, said cover-plate aperture including a radial portion conformant to the lug of the lever hub and providing for axial withdrawal of the lever when the lug and said aperture portion are angularly aligned, and said lug acting in all non-aligning angular positions thereof relative to said cover-aperture portion to interengage the cover-plate and the lever as an assembly pair for joint removal and replacement and in the installed plate condition to prevent axial separation of the lever hub and the operating element, said radial portion of the cover-plate aperture in said installed condition being angularly spaced from the lug-seating formation of the operating element in said given angular position of the latter.

7. In a strip server having a tape cutter, feed means behind the cutter to advance tape to and beyond it, and a moistener spaced forwardly of the cutter and adapted to contact the under face of the tape, a tape guiding assembly cooperatively associated with the cutter, the feed means and the moistener, said assembly comprising under and upper guide plates of a length to extend from the cutter to the moistener, means pivotally interconnecting the plates at their forward portion, a tape presser roll rotatably supported in substantially tangential relation to the forward portion of the underplate, and horizontal pivot means at the rear of the underplate supporting said assembly for vertical movement as a unit.

8. A tape guiding assembly unit for a moistened strip server, comprising lower and upper guide plates of a width at least equaling that of the maximum width of tape to be served and adapted together to define a feed channel having a rear receiving mouth and a front exit for the tape, means adjacent the channel exit pivotally interconnecting the plates for relative movement between closed and open positions, and pivotal bearing means at the rear of the lower plate for removably positioning the assembly unit on a strip server with capacity for vertical pivotal movement of the unit as a whole.

9. A tape guiding assembly unit according to claim 8 wherein the pivotal interconnecting means for the plates rotatively support a weighted transverse presser roll at the channel exit, with the lower periphery of the roll forward of and approximately tangential to the plane of the lower plate, for depressant guiding of the tape issuing from between the plates.

10. In an adhesive strip server, a housing comprising longitudinal frames defining the lateral walls for a main compartment, said frames having lateral portions at their rear ends together presenting a rear wall for said compartment, a movable top closure element pivotally mounted at the rear of said frames, said element having rear, lateral, front and top wall portions and being open downwardly to provide an upward extension of and closure for said main compartment and having concealed removable spring-retained pivotal connections with the lateral walls thereof, a front closure element pivotally supported between the front portions of said longitudinal frames for movement to and from compartment-closing relation with said frames and the forward portion of the top closure element, spring means yieldably holding the front closure

element in closed position, a longitudinal removable outwardly dished side plate at the outer face of one of the longitudinal frames and defining therewith a closed auxiliary compartment, and externally concealed means detachably interconnecting the side plate and the adjacent frame, the rear portion of the main compartment and of the top closure element together defining an enclosure for a strip supply roll, the fore portion of the main compartment and of the top closure element together with the front closure element being adapted to house strip feeding, moistening and cutting elements, and said side plate constructed and arranged to present for external availability a manual operating element for the strip server and together with the adjacent longitudinal frame to house actuating connections between such operating element and such strip feeding, moistening and cutting elements.

11. Moistening means for strip servers, comprising a generally rectangular tank of a transparent plastic composition, including opposite side, transverse and bottom walls and being open at the top, the side walls having opposed vertical channel formations at their inner faces, a partitioning wall member removably seated in the channel formations, and an inverted brush moistener receivable in the tank with its butt down and the free ends of its bristles projecting.

12. Moistening means for strip servers, comprising a generally rectangular tank of a transparent plastic composition, including opposite side, transverse and bottom walls and being open at the top, the side walls having opposed vertical channel formations at their inner faces, a partitioning wall member removably seated in the channel formations, and an inverted brush moistener receivable in the tank with its butt down and the free ends of its bristles projecting, and an upwardly projecting positioning formation transversely disposed on the tank bottom wall, said formation including transverse surfaces oppositely inclined downwardly at opposite sides of the partitioning member and adapted to direct the brush butt away from the latter.

13. In a strip serving machine, in combination, a housing including spaced longitudinal frames providing a tape roll chamber, tape feed means including a driven roll and an opposed roll cooperable to advance the tape between them, a pair of shear members transverse of the tape path, one fixed and the other movable, means providing a guiding channel for the tape between the feed means and the shear members, a tank for liquid on and between the frames below the tape path, a capillary moistener in the tank with its upper end projecting for engagement with the under face of the tape, guide means at the front of the machine housing cooperable with the moistener to receive and deliver moistened lengths of tape advanced past it by the feed means, a presser roll adapted to bear on the upper face of the tape to effect moistening engagement of its under face with the moistener, a bottom guide for the tape between the shear members and the moistener, said guide having a forward portion rotatably supporting the presser roll and being pivoted on the frames at its rear portion for vertical movement about a horizontal axis closely in advance of the shear members, and an upper tape guide carried by the bottom guide,

said guides adapted to conduct the tape below and in tangential relation to the presser roll and having rearwardly divergent rear edge portions to receive the leading end of the tape from the shear members in various angular positions of the pivoted bottom guide.

14. In a strip serving machine, in combination, a housing including spaced longitudinal frames providing a tape roll chamber, tape feed means including a driven roll and an opposed roll cooperable to advance the tape between them, a pair of shear members transverse of the tape path, one fixed and the other movable, means providing a guiding channel for the tape between the feed means and the shear members, a tank for liquid on and between the frames below the tape path, a capillary moistener in the tank with its upper end projecting for engagement with the under face of the tape, a presser roll adapted to bear on the upper face of the tape to effect moistening engagement of its under face with the moistener, a bottom guide for the tape between the shear members and the moistener, said guide having a forward portion rotatably supporting the presser roll and being pivoted on the frames at its rear portion for vertical movement about a horizontal axis closely in advance of the shear members, and an upper tape guide carried by the bottom guide, said guides adapted to conduct the tape below and in tangential relation to the presser roll and having rearwardly divergent rear edge portions to receive the leading end of the tape from the shear members in various angular positions of the pivoted bottom guide.
